UNITED STATES PATENT OFFICE.

ERNEST W. PRIGAN, OF CHICAGO, ILLINOIS, ASSIGNOR OF ONE-HALF TO OSCAR F. SCHMIDT, OF CHICAGO, ILLINOIS.

VALVE AND LOCK.

1,175,557.

Specification of Letters Patent. Patented Mar. 14, 1916.

Application filed May 13, 1915. Serial No. 27,767.

To all whom it may concern:

Be it known that I, ERNEST W. PRIGAN, a citizen of the United States, residing at Chicago, in the county of Cook and State 5 of Illinois, have invented certain new and useful Improvements in Valves and Locks, of which the following is a specification.

One of the objects of my invention is to provide a valve in a conduit carrying the 10 gases to or from an engine, the casing of which is an integral part of the conduit, and a lock controlling the valve and which is inseparable therefrom, the casing of which is a substantial integral part or 15 equivalent of the conduit and of the valve casing, or in fixed association therewith, whereby the lock and valve may not be removed from place except by machine shop procedure.

20 The essence of the invention consists, among other things, in providing means for closing the ingress or egress gas path to or from the engine and the inseparable locking means therefor to prevent unauthorized starting of the engine.

Another object of my invention consists in generally improving locks for automobiles and the like.

Other and further objects of my invention will become readily apparent to persons skilled in the art from a consideration of the following description when taken in conjunction with the drawings wherein:—

Figure 1 is a side elevation of a typical 35 internal combustion engine as applied to an automobile, showing the intake side. Fig. 2 is an enlarged central section, taken on line 2—2 of Fig. 5, through the conduit, between the carbureter and manifold, showing the valve and lock in place and the valve closed and locked. Fig. 3 is a central vertical section taken on line 3—3 of Fig. 8. Fig. 4 is a view similar to Fig. 2 showing the valve open. Fig. 5 is a section taken 40 just above the valve on line 4—4 of Fig. 2. Fig. 6 is a transverse section taken on line 6—6 of Fig. 2. Fig. 7 is a transverse section taken on line 7—7 of Fig. 2. Fig. 8 is a front elevation of the dial plate of 45 the permutation lock, as it appears on the instrument board of an automobile.

In all the views the same reference char-

acters are employed to indicate similar parts.

In the drawings I have shown one exemplification of my invention wherein the device is inseparably fixed between the carbureter 10 and the intake manifold 11 of the engine 12. The object of making the device in this manner is to render it practically impossible for a person outside of the machine shop or unsupplied with proper tools to conveniently remove any part of the device so that without considerable noise and expenditure of time a novice, or 55 a person unacquainted with machine shop practices and appurtenances cannot hurriedly open the lock by removing parts and thereby place the engine in condition 60 for operation.

70 For mechanical purposes and to simplify and cheapen the construction, I have shown the housing or casing of the lock 14 and the valve 15 made of plates 16 and 17, riveted together at their marginal edges, as 75 at 18. The pipe or conduit 19 leading to the header 11 is fitted inseparably in the casting 16 and in like manner the pipe or conduit 20, which leads to the carbureter 10, is fixed to the plate or casting 17. Between these two pipes is a gate valve 21, shown closed in Figs. 2 and 5 and shown open in Fig. 4. In closed position, as shown in Fig. 2, it will be clearly seen that gases cannot be drawn from the carbureter 80 through the pipe 20 into the pipe 19 leading into the header 11, but when the valve is open, as shown in Fig. 4, there is provided an unobstructed passage-way between the pipes 19 and 20 so as not to impose any 85 additional friction by the valve upon the moving gases. Thus we have in the above described structure a two part casing separable in a horizontal plane, carrying a 90 slideable valve and arranged for insertion 95 in the cut away portion of the gas intake pipe, the casing parts being secured to the adjacent ends of the intake duct.

Attached to the gate valve 21 is a rod 22, as at 23. The rod 22 with the valve 21 100 is freely slideable in apertures 24 and 25, respectively, made in the casing castings 16 and 17. If it were not for the lock 14 the valve 21 and rod 22 could be freely moved

into closed and open position at any time by pulling on the knob 26, which is on the face side of the instrument board 27 and which is connected to an angularly disposed rod 28, secured to the rod 22, as at 29, as shown in Fig. 3. To prevent the movement of the valve, controlling the conduit for the gases leading to or from the engine, I provide a lock 14 and for convenience of use and operation I prefer to provide a combination or permutation lock. I provide an enlargement 30 in the upper casing half, to house the lock mechanism, which consists of a rotary tumbler 31 fixed to the rotatable shaft 32 and notched or cut away, as at 33, to clear the rod 22, as shown in Fig. 6. The tumbler 31 is secured to the shaft 32, by a pin 34. The tumblers 35 and 36 are both loose upon the shaft 32 and each tumbler is provided with a notch 33. A collar 38 is secured to the shaft 32 and prevented from rotating thereon by a screw 31, for fixing it to the shaft. The tumbler 35, is loose on the shaft. A cross pin 40 passes through the shaft and is contained in the counter-bored recess 41 of the tumbler 35. Projecting laterally from the tumbler 35 is a coacting pin 42 which is adapted to contact the pin 40 when the shaft is rotated for the purpose of moving the tumblers. Another pin 43 passes through the shaft and is adapted to make intimate contact with the pin 44 that projects inwardly from the tumbler 36 within the chamber 41 or 35 counter-bore in the main tumbler 36.

Seated on the peripheral surfaces of the tumblers 35 and 36 are friction producing springs 45 and 46 which are secured to the housing, as by screws 47—47. The object of these springs is to frictionally hold the tumblers 35 and 36 in the positions in which they have been placed through the instrumentality of the rotating shaft 32 and the contacting pins secured thereto, when the respective tumblers have been rotated in counterdirection as common with permutation locks.

Each of the tumblers is provided with a flange, as 50, and a part or drum of smaller diameter, as 51. The rod 52 is cut away, as at 53, so that the flange and drum parts of the tumbler 31 may enter cut away portion of the rod. The rod 22 is also cut away, as at 53, and 54, for like purposes for the respective tumblers 35 and 36, and when portions of the tumblers are within these cut-away portions of the rod 22, it will be impossible to slide the rod 22 and thereby to move the valve 21. The opening to the recess in the housing 30 is closed by an upstanding projection on the lower casing part thus completely inclosing the lock mechanism.

To rotate the shaft 32, in order to move the tumblers to their proper relative posi-

tions in register with the rod 32 at a remote point from the lock, as from the instrument board of an automobile, I provide a flexible shaft 55 secured to the outer end of the rod 32, as at 56, and lead it up through the instrument board 27 of the automobile. The other end of the shaft 55, is connected to a stud 56 carrying a dial plate 57 and a knob 58. When the dial plate 57 is rotated by the knob, with reference to the fixed point 59, the tumblers may thereby be moved to positions where the cut-away portions 33 register to permit movement of the rod 22, so that the valve 21 may be withdrawn from its closed position by pulling on the knob 26 and moving it to the dotted line position shown in Fig. 3. To close the valve it is only necessary to push the knob 26 back to the position shown in full lines in Fig. 3, when the valve 21 will be moved to close the opening between the conduits 19 and 20. The lock mechanism is common in arrangement and operation with the usual permutation locks of the same general character.

It is of course manifest that the valve and lock could be applied to the exhaust outlet of an engine and accomplish the object desired and furthermore that it can be used in connection with a steam or air engine with equal facility.

While I have herein shown a single embodiment of my invention for the purpose of clear disclosure it is apparent that changes may be made in the material specified and in the disposition of the parts, within the spirit and scope of my invention.

Having described my invention, what I claim is:

1. In combination with a duct communicating with the cylinder of an internal combustion engine, of a two-part casing associated with the duct, its parts being joined in a plane at right angles to the axis of the duct, a duct closing valve slidable in said casing, a valve locking mechanism carried in a recess formed in one part of the casing and a projection on the other part of the casing adapted to close the opening in said recess and secure the locking mechanism in position.

2. In combination with a duct communicating with the cylinder of an internal combustion engine, and having a transverse section thereof cut away, of a two-part casing surrounding said cut-away portion of the duct, one part of the casing secured to the duct at one side of the cut away portion and the other part secured to the duct at the opposite side of the cut away portion, the two parts of said casing being joined in a plane at right angles to the axis of the duct, a slidable duct closing valve moving in the plane of juncture between the two parts of the casing, a valve locking mechanism car-

ried in a recess formed in one part of the casing, and a projection on the other part of the casing adapted to close the opening in said recess and secure the locking mechanism in position.

In testimony whereof I hereunto set my

hand in the presence of two subscribing witnesses.

ERNEST W. PRIGAN.

In the presence of—

FORÉE BAIN,

MARY F. ALLEN.
